JOHN HOUTP, OF SPRINGTOWN, PENNSYLVANIA.

Letters Patent No. 97,923, dated December 14, 1869.

IMPROVEMENT IN CONDENSERS.

The Schedule referred to in these Letters Patent and making part of the same.

To all whom it may concern:

Be it known that I, JOHN HOUTP, of Springtown, county of Bucks, State of Pennsylvania, have invented an Improved Condenser for Steam-Engines, &c.; and I do hereby declare the following to be a full, clear, and exact description of the same.

My invention consists of a jet-condenser, so constructed and operating that the condensing-water and condensed steam shall be carried off by gravity alone, while all particles of air shall either pass off with the water or be exhausted from the condenser by means of a small air-pump, all of which is fully described hereafter.

In order to enable others skilled in the art to make and use my invention, I will now proceed to describe its construction and operation, reference being had to the accompanying drawing, which forms a part of this specification, and in which—

Figure 1 is a vertical section of my improved condenser, in the simplest form;

Figure 2, a sectional view of a modification of my invention, in which the condensing-water has to be raised to a certain height before performing its duty; and

Figure 3, another modification, to be used when but a small supply of condensing-water can be obtained.

Similar letters refer to similar parts throughout the several views.

Before proceeding to describe my invention, it will be well to state that its object is to effect economy in the condensation of steam, by dispensing, either wholly or in part, with the air-pump, as an adjunct to jet-condensers.

It may be also mentioned, that the apparatus is intended to be used mainly in mountainous or hilly country, where a regular supply of running water, having from thirty to fifty feet fall, can be obtained, although it can be used advantageously in the upper story of a building, or, in fact, in any situation of a proper height, to which a sufficient head of condensing-water can be conducted.

On reference to fig. 1 of the drawing—

A represents the condensing-chamber, consisting, in the present instance, of an upright cylindrical vessel, with which communicates, at the top, the exhaust-pipe B of the engine.

The pipe C, by which the condensing-water is conducted to the apparatus, passes through one side of the vessel A, and to the funnel-shaped bottom a of the latter is connected the upper end of a vertical tube, D, through which the condensing-water, the condensed steam, and all particles of air are carried off from the apparatus, as described hereafter.

One end of the tube c is connected to a tank, F, into which a constant stream of water is conducted

by a spout, b, and the opposite end of the said tube, within the condensing-vessel, is bent abruptly downward, as shown in the drawing, and terminates in a rose, h, from the centre of which projects a tapering nozzle, i.

The lower end of the tube D also projects into a tank, H, filled with water, and in order to prevent this water from rising through the tube into the condensing-vessel, when a vacuum is produced within the latter, it is necessary that the said tube should be of greater length than the height of a column of water which would be forced upward through the same by the pressure of the atmosphere; in other words, the length of the tube must exceed thirty-four feet.

At the lower end of the tube D is a valve-chest, j, which is furnished with four hinged valves, k, opening outward into the tank, and on one side of the tube, above this valve-chest, but beneath the water-line in the tank, is an opening, covered by a sliding valve, l, which is operated by means of the rod l'.

There is also, on the tube D, a cock, m, for a purpose described hereafter.

The operation of the apparatus is as follows:

Before admitting steam, the cock r, in the pipe C, is closed, and the cock m and valve l of the tube D opened, steam from the exhaust-pipe B being then blown through the chamber A and tube D, for the purpose of driving out the air.

When the air has been entirely expelled, the cock m is closed, and the cock r opened, water then flowing through the pipe C, and passing from the rose h into the condensing-chamber, in a number of fine jets, while a stream of water is projected with considerable force from the nozzle i directly into the tube D, to which the air and water are guided by the funnel-shaped end of the chamber.

These jets of water will immediately condense the steam contained in the apparatus, when a vacuum being formed, water will be forced from the tank H through the valve-opening l, and up into the tube D, to the point represented by the line x-x, fig. 1, or, in other words, to a height of about thirty-three feet, the valve l being then closed.

As each puff of exhaust steam enters the condensing-chamber, it will force whatever air has accumulated in the same downward, and through the cold-water jets, the latter immediately condensing the steam, and forcing the same, together with the air, into the tube D, the volume and force of the jets, and of the stream from the nozzle i, being sufficient to thoroughly mix the water and air in the tube, and to prevent the air from again rising into the condensing-chamber, it consequently passing downward with the water to the lower end of the tube, and escaping through the valves k.

It will be understood, that when the water has once risen in the tube D to the height shown by the line $x-x$, it is maintained at that point by the supply of condensing-water and condensed steam, the surplus water passing into the tank H through the valves k , which will open when the pressure of the column of water in the tube exceeds that of the atmosphere, or when it rises above the line $x-x$.

It will be evident, without further description, that a condenser, constructed and operating as above described, will possess the advantages over the ordinary jet-condenser, of maintaining as good or a better vacuum, at less expense, and without taxing the engine for a portion of its power to drive an air-pump.

When a plentiful supply of condensing-water can be obtained, but at a height somewhat less than that of the condensing-chamber, it will be necessary to construct the apparatus as shown in fig. 2.

In this case, a vacuum is first produced, after blowing through, by means of what I term a "primer," being merely a short tube, s , terminating in a rose, and communicating with an adjacent tank. After producing the desired vacuum, the pressure of the atmosphere will be sufficient to cause a constant stream of water to rise through the tube c and into the condensing-chamber.

In other cases, where the supply of water is limited, and barely sufficient to condense the steam, the apparatus may be constructed as seen in fig. 3, the nozzle i being, in this case, dispensed with, and a small air-pump being attached to the condenser, for the purpose of exhausting the air from the same; but it should be understood, that even in this case the condensing-water and the condensed steam are carried off

through the tube D, so that the power required to drive the air-pump amounts to but little.

The valves k , at the lower end of the tube D, are not essential to the perfect working of the apparatus, their object being to prevent the sudden fluctuations of the height of the water in the tube, in the intervals between the admission of each puff of steam and its condensation.

Although I have described my invention as applied to a steam-engine only, it will be evident that it can be advantageously employed in connection with sugar-boilers' vacuum-pans, and for other useful purposes.

I claim as my invention, and desire to secure by Letters Patent—

1. Chamber A, pipe D, and tubes B C, so arranged that a stream of water is forced through the said chamber, directly into the mouth of the tube D, substantially as described.

2. A rose, h , constructed and applied to the condenser, substantially as set forth.

3. The valves k and l , arranged at the lower end of the tube D, substantially as specified.

4. The chamber A, its tube D, and supply-pipe C, in combination with the primer s , as described.

5. The combination, with the tubes B, C, and D, arranged as described, of a chamber, A, having a funnel-shaped bottom, for the purpose set forth.

In testimony whereof, I have signed my name to this specification, in the presence of two subscribing witnesses.

JOHN HOUPt.
